The ornamental design for a dj mixer, as shown.

DESCRIPTION

Djs use a dj mixer for mixing the audio signals of two phonograph players. They also use the volume faders and cross-fader as manipulators made into plural units to be used during play in real-time.

FIG. 1 is a top plan view of a dj mixer showing my new design;

FIG. 2 is a right side elevational view thereof;

FIG. 3 is a left side elevational view thereof;

FIG. 4 is a front elevational view thereof; and,

FIG. 5 is a rear elevational view thereof.
